UNITED STATES PATENT OFFICE.

HENRY J. HERBERT, OF DETROIT, MICHIGAN, ASSIGNOR TO UNITED STATES CHEMICO WOOD COMPANY, OF DETROIT, MICHIGAN, A CORPORATION OF MICHIGAN.

DESIGN FOR A MIRROR-FRAME.

SPECIFICATION forming part of Design No. 35,575, dated January 14, 1902.

Application filed December 16, 1901. Serial No. 86,162. Term of patent 7 years.

To all whom it may concern:

Be it known that I, HENRY J. HERBERT, a citizen of the United States, residing at Detroit, in the county of Wayne and State of Michigan, have invented and produced a new and original Design for a Mirror-Frame, of which the following is a specification, reference being had therein to the accompanying drawings.

Figure 1 is a plan view of a mirror back and handle, showing my design; and Fig. 2 is an edge elevation thereof.

As shown in the drawings, the leading or material feature of my design consists of a tapering handle or frame merging into a circular disk, the handle and back being provided with broken irregular vein-like orna-

mentation, which on the disk extends across the face thereof.

A represents the handle, and B the body or disk, and C the vein-like raised broken ornamentation. The handle terminates in the inclined flange or rib D.

Having described my invention, what I claim as new, and desire to secure by Letters Patent, is—

The design for a mirror-frame, as herein shown and described.

In testimony whereof I affix my signature in presence of two witnesses.

HENRY J. HERBERT.
